UNITED STATES PATENT OFFICE.

WILLIAM SCHACK, OF NEW YORK, N. Y.

AUTOMATICALLY-OPERATED FOOT-PEDAL FOR PLAYER-PIANOS.

1,304,605.

Specification of Letters Patent. Patented May 27, 1919.

Application filed January 10, 1916. Serial No. 71,209.

To all whom it may concern:

Be it known that I, WILLIAM SCHACK, a citizen of the United States, and resident of the borough of Manhattan, city, county, and State of New York, have invented certain new and useful Improvements in Automatically-Operated Foot-Pedals for Player-Pianos, of which the following is a specification.

10 The device, which I am about to describe is an electromagnetic means for obtaining a movement of the pedal or bellows of a player piano and is of a similar construction to that shown in my co-pending application 15 Serial No. 91,256, filed April 14, 1916.

In the past this useful operation has usually been accomplished by means of the feet of the operator or by an electric or mechanical motor.

20 My device is designed with a view of simplifying the attachment of an electrically operating device to make unnecessary the complicated mechanisms used for reducing the speed of a motor and also to do away 25 with the mechanical sounds produced by the motor-speed-reducing parts and the several mechanical connections which it has been found necessary to employ.

My device is so constructed that it can be 30 attached to an ordinary player piano without material change in the construction of the piano and when so attached and with but slight readjustment of a part, the piano may be operated by foot power. My principal aim then is simplicity and efficiency 35 and to that end I employ the mechanisms and in the manner to be described.

The following is what I consider a good means of carrying out this invention and the 40 accompanying drawings form part of this specification in which

Figure 1 is a perspective view of the piano, showing the application of my improvement thereto;

45 Fig. 2 is a detail view showing a means for obtaining an alternate movement of the pedals;

Fig. 3 is a diagram of the circuit connections;

50 Fig. 4 is a partial sectional view on an enlarged scale, of the operating device alone;

Fig. 5 is a plan view of a switch operating mechanism; and

Fig. 6 is an elevation of the same.

Similar reference numerals indicate like parts in all the figures where they appear.

In Fig. 1, I have shown an ordinary player piano as indicated at 1, which may be of any general design shape and size. The keyboard is shown at 2 and under the keyboard a front board 3 is shown which is provided with an aperture 4 adjacent to which are arranged a plurality of pedals 5 and 6. The pedals are connected through the aperture 4 with the bellows of the piano. All of the parts thus far described require no change in their application to my invention and therefore they will require no detailed description as it is thought that their construction, their relation and their operation are fully understood.

Secured to the front board 3 is a small cabinet 7 within which I arrange the operating mechanism for a rod 8 which rod terminates in a crossbar 9 impinging upon each of the pedals 5 and 6.

The operation of the rod 8 will cause an operation of the pedals and it is with the means for operating this rod that this application has to do and therefore I refer to Fig. 2 where the operative mechanism is shown in detail.

Arranged within the cabinet 7 is a solenoid 10 having a movable plunger 11 which plunger is, upon the energizing of the coil 10, caused to assume a central position within the coil.

Normally the core or plunger 11 will be elevated by the action of the ordinary pedal return springs upon the crossbar 9 and rod 8, the rod 8 being connected by means of a hinge block 12 to a plug 13 which is screw-threaded into the lower end of the core 11.

The core 11 being normally elevated the coil 10 will tend to draw the core 11 downward when the coil is energized from a convenient source of electric current supply and will retain the core in its lowermost position during such time as the current continues to flow through the coil 10. This downward movement of the core will through the rod 8 and crossbar 9 depress both of the pedals 5 and 6.

Associated with the core 11 is a switch mechanism for supplying current to the coil 10 to move it in one direction and for cutting off the supply of current at the end of

such movement to permit the return of the core.

A source of current supply, not shown, is connected to one blade 14 of the uppermost switch member by conductor 27 as shown in the diagram of Fig. 3 and a jumper or wire connection 15 continues from the source of current supply to one side 16 of the lowermost switch member. The other lead 28 from the current supply passes through the coil 10 and terminates at the other side 17 of the lowermost switch member and is also connected by wire 33 with the second blade 18 of the uppermost switch member.

15 A plug 19 is secured to an arm 20 which is adjustably supported upon the core 11 and when this plug 19 is introduced between the blades 14 and 18 of the uppermost switch member current will pass through 20 the coil 10.

The lowermost switch member consists of a plug 21 movable in the bracket 22. The forward end of the plug 21 is fitted with a soft iron button 23 and the outer 25 end supports a resilient arched member 24 which, when the switch is closed, makes contact between the contacts 16 and 17 completing the path across these contacts. A spring 25 urges the plug 21 outward to open 30 the contact closed by the member 24.

When the coil 10 is energized and the core 11 magnetized, the magnetic flux will draw the button 23 and plug 21 against the force of spring 25 toward the core 11 and close 35 the path or circuit between the contacts 16 and 17. This circuit or path will remain closed until a projection 26 upon the core 11 forces the button 23 away from the core 11 to an extent sufficient to open the path 40 between the blocks 16 and 17.

In the operation of the device the current is allowed to flow through the leads 27 and 28 to the clips 14 and 18 of the upper switch member, the path of the current 45 being through the coil 10. When the plug 19 closes the circuit between the clips 14 and 18 the coil will be energized and the core 11 magnetized. At this time the core will not start to travel downwardly before 50 the button 23 is drawn inward to an extent to close the second path for the current supply which path is through the contacts 16 and 17. Now even though the plug 19 leave the clips 14 and 18 current will continue to 55 flow through the coil at this time through the secondary circuit via the contacts 16 and 17 and the arched member 24. The flow will continue until the projection 26 impinges upon the button 23 to an extent 60 sufficient to move the member 24 outwardly and break the circuit across the contacts 16 and 17. This interruption may cause an arc due to the discharge or kick of the coil 10. The discharge will be taken up by a suitable

condenser 29 in a circuit between the wire 65 15 and the wire 33 and the member 24 and contacts 16 and 17 will not be injured by the discharge.

The movement of the coil operating the rod 8 will depress both pedals 5 and 6 and 70 when the circuit is broken by the completed movement of the core 11 the springs which assist in the operation of the pedals 5 and 6 will return the core 11 to its uppermost position reestablishing the circuit through the 75 clips 14 and 18 and by magnetizing the core the circuit will be completed across the blocks 16 and 17 and a second cycle of operation will ensue. The arm 20 is made adjustable so that the period during which 80 the plug 19 is in contact with the clips 14 and 18 may be varied at will.

I provide a spring 30 adjacent to the upper end of the plunger 11 which takes up the shock of the return of the button 85 25 should current be cut off when the spring 25 is compressed.

In the early description of the apparatus I have indicated that both pedals were operated in unison but it is possible that some 90 would prefer an alternate operation of the pedals, to this end I have provided a rocker arm 50 (Fig. 3) which is connected to a lever 51 to which the rod 8 is secured. From the rocker arm 50 pivoted levers 52 95 and 53 are attached to the pedals 5 and 6 and the movement of the rod 8 in either direction will cause an alternate movement of the pedals 5 and 6. If this construction is utilized it will possibly be necessary to 100 employ an additional spring 54 for obtaining a reverse or upward movement of the rod 8. Other modifications may be made within the scope of the appended claim without departing from the principles or 105 sacrificing the advantages of the invention.

The plug 13 and the hinge 12 (Fig. 4) should be of brass or some other non-magnetic material. The rod 8 may be of wood and I may allow the crossbar 9 to bear upon 110 the pedals 5 and 6 without securing it there-to so that when desired the pedals may be operated by foot power in the ordinary manner. Any other suitable mechanism may be employed and the sizes and arrangement of the separate parts may be changed 115 to cause them to comply with other requirements.

It will of course appear quite obvious that my device may be attached to an organ or 120 to any other musical instrument having the general means of operation as herein set forth.

It will further appear that I may not be confined to the use of an electro-magnet 125 having a movable core, but that a magnet may be employed in which the coil or casting may be moved or an armature that is

not the core may constitute the movable member.

Having carefully and fully described my invention what I claim and desire to secure 5 by Letters Patent is:—

The combination with a musical instrument having an operating mechanism provided with a pedal which is spring-pressed in one direction and adapted to be positively 10 moved in the other direction, of a solenoidal electromagnet having its core connected

with said pedal for positively moving the latter in opposition to its spring, and a circuit controller for alternately closing and opening the circuit of the solenoid. 15

Signed at New York city this 4th day of January, 1916.

WILLIAM SCHACK.
